DESIGN FOR A TRANSPARENCY MOUNT

Thomas L. O'Toole, Rochester, N. Y., assignor to
Eastman Kodak Company, Rochester, N. Y., a
corporation of New Jersey

Application May 8, 1942, Serial No. 106,820

Term of patent 14 years

To all whom it may concern:

Be it known that I, Thomas L. O'Toole, a citizen of the United States, residing in Rochester, in the county of Monroe and State of New York, have invented a new, original, and ornamental Design for a Transparency Mount, of which the following is a specification, reference being had to the accompanying drawing, forming part thereof.

In the drawing:

Fig. 1 is a front elevational view of a transparency mount showing my new design.

Fig. 2 is an end elevational view of the mount.

Fig. 3 is a rear elevational view of the same.

Fig. 4 is a perspective view of the front of the same.

I claim:

The ornamental design for a transparency mount, as shown.

THOMAS L. O'TOOLE.
